(57) **CLAIM**

The ornamental design for a squeezable bottle, as shown and described.

DESCRIPTION

FIG. 1 is a front elevational view of a squeezable bottle in a first configuration, the back, left side and right side views being identical thereto;

FIG. 2 is a front, side perspective view thereof;

FIG. 3 is front elevational view of the squeezable bottle in a second configuration, the back, left side and right side views being identical thereto;

FIG. 4 is a front, side perspective view of the squeezable bottle in the second configuration shown in FIG. 3;

FIG. 5 is a top plan view of the squeezable bottle in both the first and second configurations shown in FIGS. 1 and 3, respectively; and,

FIG. 6 is a bottom plan view thereof.

The broken lines shown are included for the purpose of illustrating the unclaimed portions of the article and form no part of the claim.
